VIOLIN SUPPORT

Elgard Malvin Ungh, Stockholm, Sweden

Application January 16, 1950, Serial No. 138,717
In Sweden November 7, 1947

8 Claims. (Cl. 84—280)

1

The present invention concerns a removable support for a violin, by means of which the violin comfortably and firmly can be applied to the player's shoulder, thus making it possible to dispense with the supporting cushions generally used.

The invention is essentially characterized by the fact that the violin support has been given the shape of a hoop attachable to the sound-board of the violin, and that the end parts of the shanks of the said hoop can be lengthened and/or bent to the shape desired; the space defined by the middle portion of the hoop and the bottom of a violin mounted between the end parts of the shanks thus being variable.

This as well as other characteristics of the invention will be fully explained in the following description of the violin support according to the invention shown by way of example in the drawings enclosed.

Fig. 1 shows a form of realization of the violin support applied to the bottom side of a violin.

Fig. 2 is a section along the line II—II in Fig. 1.

Fig. 3 shows on a smaller scale how according to the player's wish the support can be turned to different positions on the violin.

Figs. 4, 5 and 6 show another form of realization of the arrangement for the attachment of the support to the violin than the one shown in Fig. 1 and 2; Fig. 4 showing the arrangement from one end and Figs. 5 and 6 being sections along the lines V—V respectively VI—VI in Fig. 4.

In the drawings 1 is the sound-board of a violin, to which is removably attached a violin support according to the invention. The violin support has been given the shape of a hoop preferably consisting of two flexible threads of metal 2. The threads 2 are located at a certain distance from one another, as seen in Fig. 2 and are connected with one another by means of cross-connections 3 and 4. The connection 4 at the middle portion of the hoop, which connection extends over the greater part of the length of the said middle portion and may be executed in two or several parts, serves as the portion resting against the player's shoulder. The middle portion of the hoop as well as the cross connection 4 should preferably be provided with a soft lining e. g. Manchester velvet or some similar material.

The shafts 5 of the hoop, which may be straight or, as shown in the drawings, approximately have the shape of an S or a double S, have their ends developed into a claw 6 intended to clutch the edge of the bottom 1 of the violin, Figs. 1 and 2. In order to secure their gripping capacity and to protect the violin the claws are provided with a lining 7 of rubber or some similar material, e. g. in the shape of sleeves applied to them.

By jamming together or drawing apart the S-shaped shanks the height of the support as well as its inclination in every direction can be varied.

2

which makes it possible for the support to be adjusted according to every player's particular wishes.

To make it possible further to adjust the height 5 and the inclination of the support the shanks can be constructed in different parts, which may telescope either into each other or into sleeves surrounding them and be fixed in different positions. The shanks and the sleeves may also be threaded at their points of partition, preferably with right hand threads and left hand threads. At such a realization of the invention it is also conceivable to make the shafts straight, i. e. without the S-shape shown in the drawing.

15 At the mode of realization shown in Figs. 4-6 the sleeves 8 are arranged to be attached direct to the violin, at least at one end of the hoop. The sleeves are by way of example fixed to a plate 9 which may be provided with a folded edge 10 resting against the side of the violin. At a point between the sleeves 8 e. g. at the middle of the plate a threaded pin 11 is joined into it. A counter pressure plate 12, preferably also provided with a folded edge 13 supports a threaded pin 14, similar to the pin 11. The plate 9 with its sleeves 8 will rest against the bottom side of the violin, and the counter pressure plate 12 against its top side. By means of turning a right hand- and left hand threaded nut or sleeve 15 20 the plates 9 and 12 can be drawn together and made to rest against the violin with the strapping on of the violin as a result. In order to protect the violin the plates 9 and 12 and if desired also their folded edges 10 and 13 may be provided with a lining 16 and 17 of cork, leather, cloth, rubber or some similar material. To facilitate the turning round of the nut 15 it should preferably be provided with a hole 18.

25 40 The shafts 5 of the hoop which can be bent if desired in an S-shape are inserted into the sleeves and kept there by the spring elasticity of the hoop. To enable the variation of the height and/or inclination of the support the ends of the shanks 5 are provided with threads 19 and nuts 20, which rest against the sleeves 8 and thus limit the insertion of the shanks into the sleeves. To prevent the sleeves 8 from the possible assuming of an oblique position they can preferably be provided with studs 21 of leather, rubber or some similar material on the side resting against the violin.

45 55 It ensues from the above that also the middle portion of the hoop can be bent into the shape desired and adjusted to the player's shoulder. and also, as shown in Fig. 3, that, when required, the support can be turned relatively to the violin, although the friction between the claws of the support and the violin is quite sufficient to keep the support in position, when used.

55 60 The middle portion of the support being quite out of contact with the violin makes it possible to obtain a considerably better tone and more resonance than is possible when employing the supporting cushions now generally used. Owing

to the elasticity of the material used for the support it is not necessary that the support should be affixed to the violin by means of tape or the like; so the application as well as the removal of the support may be executed by a simple manipulation.

It is evident that the invention is not limited to the modes of realization shown and described, but that these may be varied in several ways within the scope of the invention.

What I claim is:

1. A violin support consisting of two angularly bent members united by cross members and provided with clamping means for the attachment of the sound-board of a violin, comprising, in combination, two flexible wires extending substantially in parallel and presenting angular bent end portions with means for the strapping of the violin, a strip member mouldable to suit the contour of the player's shoulder and extending lengthwise of the two wires between their angularly bent end portions and connecting said wires between their said end portions, and cross members uniting the adjacent end portions.

2. A violin support consisting of two angularly bent members united by cross members and provided with clamping means for the attachment of the sound-board of a violin, comprising, in combination, two flexible wires extending substantially in parallel and presenting angularly bent and S-shaped end portions with rubber-lined claws at their extreme ends for the strapping of the violin, a strip member mouldable to suit the contour of the player's shoulder and extending lengthwise of the two wires between their angularly bent end portions and connecting said wires between their said end portions, and cross members uniting the adjacent end portions.

3. A violin support consisting of two angularly bent members united by cross members and provided with clamping means for the attachment of the sound-board of a violin, comprising, in combination, two flexible wires extending substantially in parallel, and presenting angularly bent end portions, a strip member mouldable to suit the contour of the player's shoulder and extending lengthwise of the two wires between their angularly bent end portions and connecting said wires between their said end portions, cross members uniting the adjacent end portions, which latter are made in two parts with threads on their adjacent ends, the threads of one of said parts being in opposition to those of the other part, a threaded sleeve cooperating with said threaded end portions of the two parts, the extreme one of which carries clamping means for the strapping of the violin.

4. A violin support consisting of two angularly bent members united by cross members and provided with clamping means for the attachment of the sound-board of a violin, comprising, in combination, two flexible wires extending substantially in parallel and presenting angularly bent end portions, a strip member mouldable to suit the contour of the player's shoulder and extending lengthwise of the two wires between their angularly bent end portions and connecting said wires between their said end portions, cross members uniting the adjacent end portions, threads on said end portions, and threaded sleeves on said end portions to receive corresponding threaded pins on the violin, the threads on said violin pins being in opposition to those of the aforementioned angular end portions.

5. A violin support consisting of two angularly bent members united by cross members and provided with clamping means for the attachment of the sound-board of a violin, comprising, in combination, two flexible wires extending substantially in parallel and presenting angularly bent end portions, a strip member mouldable to suit the contour of the player's shoulder and extending lengthwise of the two wires between their angularly bent end portions and connecting said wires between their said end portions, cross members uniting the adjacent end portions, said end portions cooperating slidably with tubular members retained on said end portions through frictional engagement and carrying clamping means for the strapping of the violin.

10 6. A violin support consisting of two angularly bent members united by cross members and provided with clamping means for the attachment of the sound-board of a violin, comprising, in combination, two flexible wires extending substantially in parallel and presenting angularly bent end portions, a strip member mouldable to suit the contour of the player's shoulder and extending lengthwise of the two wires between their angularly bent end portions and connecting said wires between their said end portions, cross members uniting the adjacent end portions, said end portions cooperating slidably with tubular members retained on said end portions through frictional engagement and carrying clamping means for the strapping of the violin.

15 7. A violin support consisting of two angularly bent members united by cross members and provided with clamping means for the attachment of the sound-board of a violin, comprising, in combination, two flexible wires extending substantially in parallel and presenting angularly bent end portions, a strip member mouldable to suit the contour of the player's shoulder and extending lengthwise of the two wires between their angularly bent end portions and connecting said wires between their said end portions, cross members uniting the adjacent end portions, said end portions being tubular and cooperating

20 30 slidably with cylindrical members retained in said end portions through frictional engagement and carrying clamping means for the strapping of the violin.

25 8. A violin support consisting of two angularly bent members united by cross members and provided with clamping means for the attachment of the sound-board of a violin, comprising, in combination, two flexible wires extending substantially in parallel and presenting angularly bent end portions, a strip member mouldable to suit the contour of the player's shoulder and extending lengthwise of the two wires between their angularly bent end portions and connecting said wires between their said end portions, which latter are threaded midway for some distance, said threaded portions cooperating with nuts adapted to support sleeves on the extreme ends of said end portions, which sleeves are connected by a cross member serving as a violin rest and having a pin fastened in the middle portion thereof, said pin being provided with left-handed and right handed threads cooperating with a correspondingly threaded sleeve, a counter plate being secured to said pin to cooperate with said violin rest for the strapping of the violin by the turning of the sleeve on said middle pin.
